TAMPER FOR WASTE PAPER CONTAINER

Clinton S. Strong, Shelton, and William C. Tiffet, Seymour, Conn., assignors to Technical Design and Development Company, Incorporated, Devon, Conn., a corporation of Connecticut

Application February 7, 1957, Serial No. 638,782

7 Claims. (Cl. 100—265)

This invention relates to a waste paper container or receptacle with an automatic tamper, and has for an object to provide a container for waste paper or similar compressible material and the like with an improved form of tamping means for tamping down the discarded material to increase the holding capacity of the container and increase the time required between emptying operations, and to provide an improved means for operating the tamper and an inlet closure means for the container or receptacle.

Another object is to provide an improved means for mounting the tamper, including a treadle means for raising it to a position at the top of the container to permit free deposit of the discarded material, and an improved connection from the treadle means to the tamper having a motion-multiplying action whereby a relatively small movement of the treadle will impart a larger desired movement to the tamper to raise it to its upper position to permit deposit of the compressible material and permit automatic operation of the tamper when released.

With the foregoing and other objects in view, we have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a front view of the container with parts broken away to more clearly show the construction;

Fig. 2 is a side view with parts broken away;

Fig. 3 is a top plan view with the top wall removed;

Fig. 4 is an enlarged side view of the forward end portion of the treadle with part of it broken away;

Fig. 5 is a bottom view looking toward the bottom of Fig. 4;

Fig. 6 is an enlarged detail view of the operative connection from the tamper operating means to the closure;

Fig. 7 is a similar view showing a slight modification;

Fig. 8 is a side view of a holding means for a receptacle within the container;

Fig. 9 is a partial end elevation and partial section thereof substantially on line 9—9 of Fig. 8;

Fig. 10 is a vertical section through the top and front walls of the container on a larger scale taken substantially on line 10—10 of Fig. 11, and

Fig. 11 is a similar section taken substantially on line 11—11 of Fig. 10.

This container is an improvement on the waste receptacle of the copending application of Clinton S. Strong, Serial No. 461,311, filed Oct. 11, 1954.

This improved container or receptacle for waste paper or similar compressible material comprises a body 1 including a front wall 2, side walls 3, rear wall 4 and bottom wall 5 forming a receptacle for waste paper and similar waste material, and its upper end is closed by a top wall 6. The bottom wall 5 is also spaced above a second bottom wall 7 providing space for the operating treadle

2

8. This container or receptacle structure is preferably of sheet metal, with suitable means for securing these walls together.

The front wall 2 is provided with an inlet or deposit opening 9 in its upper portion closed by a closure 10 preferably pivotally mounted adjacent its lower edge, as indicated at 11, so that its upper edge may swing outwardly from the closed position shown in full lines to its open position shown in dotted lines, Fig. 10. At its outer ends it is preferably provided with end walls 12 to form a sort of chute with the front wall of the closure for guiding the material into the container or receptacle. The pivotal connection 11 may be in these end walls. This closure is spring-loaded so as to close automatically when released, an effective means being a coil spring 13 connected to the body structure at its lower end 14 and to one of the end walls of the closure at its upper end 15.

Within the container is a tamper 16. This is a weighted member of considerable weight and may be of different shapes, but preferably is substantially circular with a downwardly and inwardly tapered, preferably inverted conically shaped lower surface 17 for better tamping effect, and its upper surface 18 also may be conically shaped. This tamper is mounted for free up and down movement to tamp the loose papers or similar material in the container so that it will compress them to a smaller volume and the container will hold more than it would otherwise, thus increasing the time intervals between the necessity of emptying the container. For this purpose the tamper is freely supported by a coil spring 19 connected at its lower end to the weighted member 16, and to permit the use of a longer spring for greater movement of the tamper and reduce the necessary space required, the member 16 is provided with a vertical passage 20 therethrough in which the spring is located, and connected at its lower end 21 to the weighted member by any suitable means, such, for example, as a washer 22. The passage therefore provides an enclosing positioning means for the spring, which retains the tamper in the upright position and the spring projects from the top of the weighted member and is secured at its upper end to an attaching means 23. The spring therefore forms the sole support for the weighted member and suspends it freely within the container or receptacle above the waste material therein.

45 The spring is suspended from a flexible cable 24 passing over a guide pulley 25 in the top of the container over the weighted member and mounted on any suitable support such, for example, as supporting brackets 26 mounted on a cross wall 27, and passes over a second pulley 28 mounted adjacent one corner of the container on suitable brackets 28a and down around and under an operating pulley 29 mounted on the treadle 8 with its free end extending upwardly from this pulley and anchored at 30 above the pulley to any suitable part of the container, as, for example, the bottom wall 5. The treadle may be of any suitable construction, but that shown comprises a flat bar 31 pivoted at its rear end at 32 to a suitable bracket 33 mounted in the container structure between the bottom walls 5 and 7. At its forward end it projects through an upright slot or opening 34 in the front wall 2 where it is in a position easily accessible for depression by a foot of the operator. The pulley 29 is mounted on this treadle adjacent the front end thereof, it being secured to the treadle by any suitable means such, for example, as the bracket or housing structure 35, and there may be mounted a suitable tread 36 on the front end of the treadle, such, for example, as a rubber pad or similar device.

70 There is also an operative connection from this cable 24 to the closure 10. This may be of different constructions, but a simple and effective construction is that

shown comprising a second flexible cable 37 connected at its upper or inner end to a bracket 38 mounted on the closure and passing over a guide pulley 39 and downwardly to a connecting block 40 slidable on the cable 24. Above the block 40 secured on the cable 24 is a stop 41 preferably in the form of a ball, and on the cable 37 below the block 40 is secured a similar stop or ball 42. By locating the ball 41 a desirable distance above the block 40 there is a lost motion effected between the cable 24 and the cable 37, which permits a certain amount of movement of the cable 24 before shifting the block 40 to operate the closure 10. This is desirable as less motion is required for opening the closure than for lifting the tamper weight 16. A still further lost motion action may be effected by mounting a spring 43 on the cable 37 below the block 40 between this block and the stop ball 42. This will permit the block to slide on cable 37 for further movement of the cable 24 and block 40 after the closure reaches its extreme outer position. This provides a safety feature which, as indicated, will permit movement of the cable 24 after the limit of movement of the closure, and does away with the necessity of accurately locating the two stops 41 and 42 for operating the closure. A suitable enclosing means or guard 44 may be provided at the inner side of the front wall 2 about the cables 24 and 37 and the connecting block 40 to prevent interference with their operation by clogging from the waste paper or other material deposited in the container.

The material may be tamped directly in the receptacle formed by the side and bottom walls, and removed through a door in the rear wall, or if preferred, an auxiliary or removable container such as a metal basket or a large paper bag 45 may be provided and held in its upright open position to receive the waste material by a suitable number of spring clips 46 mounted on removable rods 47 at opposite sides of the container, the rods being supported at their opposite ends in suitable angle brackets 48 and seating in recesses 49 opening through the tops of these brackets.

In operation, depressing of the outer free end of the treadle 8 from its full line to its dotted line position of Fig. 2 will shift the pulley 29 carried by this treadle downwardly, and this pulley operating on the cables 24 will by a two-to-one ratio, because of movement of this pulley and the anchored end 30 of the cable, give twice as much motion to the cable 24 and the weighted tamper 16 as is imparted to the pulley 29. This will raise the weighted tamper 16 above the level of the opening 9 for the closure 10, permitting waste material to be deposited through this opening into the receptacle or container under the weighted tamper. At the same time, this movement of the cable will open the closure 10 through the connecting block 40 and cable 37, but there is a certain amount of lost motion provided, as previously indicated, because there is not as much motion needed to open the closure as is required for lifting the weighted tamper. After the waste material has been deposited in the container, the operator merely releases the treadle 8, which permits the closure to swing to the closed position under action of the spring 13 and at the same time permits the weighted tamper 16 to fall. As this weighted member is freely supported by the spring 19, which forms the sole support for this member, the momentum of the falling movement of the weighted member causes it to continue to fall after the treadle reaches its upper position, to stretch or tension the spring 19, and then this tensioned spring again raises or shifts the tamper 16 upwardly, and this member continues a series of up and down movements until an equilibrium is reached between the weight of this member and the spring. During this movement the tamper has a very effective tamping action on the loose material such, for example, as paper towels and the like, which have been deposited in the container, and this tamping action is further facilitated and increased and the length and duration of the reciprocating move-

ment is increased by the tapered lower surface 17 of the tamper, as the surface engaging the loose material for compressing them, because of this taper, increases progressively from a minimum to a maximum, instead of immediate maximum pressure, as would be the case if the surface were flat. This weighted member has a very effective tamping and compressing effect on the loose material deposited in the container to materially reduce its volume, and this action is secured automatically without any further operations required by the user of the device than merely the operation of depressing the treadle to open the closure to permit deposit of the material in the container, which at the same time raises the tamper to its upper position, and then the mere release of the treadle permits the tamper to operate automatically for the paper compression and tamping operation. This device is particularly adapted for use wherever compressible material has to be disposed of, such as in an office or rest room adjacent to a washbowl, for use with paper towels or the like, and a paper towel dispenser may be mounted on the top of the container, or it may be used in any location where it is desired to have a receptacle for compressible material, and where it is desirable to increase the time intervals between necessary emptying operations for the container or receptacle.

Having thus set forth the nature of our invention, we claim:

1. A container for waste material such as paper, comprising side and bottom walls forming a receptacle, one of the side walls provided with an inlet opening adjacent the top thereof, a closure for said opening spring-loaded to close automatically, a vertically movable weighted tamper in the receptacle, means for freely suspending the tamper comprising a coiled spring connected at its lower end to the tamper, a flexible cable connected to the upper end of the spring, a depressible treadle at the lower part of the receptacle, a pulley carried by the treadle, guide pulleys at the upper part of the receptacle, said cable passing from the spring over the upper and treadle pulleys and anchored at its lower free end to the receptacle, and an operative connection from the cable to the closure to open the closure on depression of the treadle.
2. A container for waste material such as paper comprising side and bottom walls forming a receptacle, one of the side walls provided with an inlet opening adjacent the top thereof, a closure for said opening spring-loaded to close automatically, a vertically movable weighted tamper in the receptacle, means for freely suspending the tamper comprising a coiled spring connected at its lower end to the tamper, a depressible treadle at the lower part of the receptacle, a pulley mounted on the treadle, guide pulleys at the upper part of the receptacle including a pulley above the tamper, a flexible cable connected to the upper end of the spring forming the sole support for the tamper passing over the latter pulley and passing under the treadle pulley and anchored to the receptacle at its free end above this pulley, and an operative connection from the cable to the closure to shift it to the open position on depression of the treadle.
3. A container for waste material such as paper comprising side and bottom walls forming a receptacle, a vertically movable weighted tamper in the receptacle, means for freely suspending the tamper comprising a coiled spring connected at its lower end to the tamper, means connected to the upper end of the spring to support it and the tamper and raise the tamper to the upper part of the receptacle including a flexible cable, a depressible treadle at the lower part of the container, guide pulley means above the tamper, a pulley carried by the treadle, and said cable passing from its connection with the spring over said pulley means and downwardly around under the treadle pulley and anchored at its free end above this pulley to raise the tamper on depression of the treadle and permit the tamper to fall of its own weight and reciprocate up and down on release of the treadle.

4. A container for waste material such as paper according to claim 3 in which the tamper has a substantially inverted conically shaped lower tamping surface and an upright central passage in which the spring is located, and means connecting the lower end of the spring to the tamper adjacent the lower end of said passage.

5. A container for waste material such as paper according to claim 3 in which there is an inlet opening in a side wall adjacent the top thereof, a movable closure for said opening spring-loaded to move automatically to the closed position when released, and a lost motion connection from the cable to the closure to shift the closure to open position on depression of the treadle.

6. A container for waste material such as paper comprising side and bottom walls forming a receptacle, one of the side walls provided with an inlet opening adjacent the top thereof, a closure for said opening spring-loaded to close automatically, a vertically movable weighted tamper in the receptacle, means for freely suspending the tamper comprising a coiled spring connected at its lower end to the tamper, means connected to the upper end of the spring to support it and the tamper and raise the tamper to the upper part of the receptacle including a flexible cable, guide pulley means above the tamper, a depressible treadle at the lower part of the container, a

5
pulley carried by the treadle, said cable passing from its connection with the spring over said guide pulley means and around under the treadle pulley and anchored at its free end above this pulley to raise the tamper on depression of the treadle and permit the tamper to fall of its own weight and reciprocate up and down on release of the treadle, and an operative connection from the cable to the closure comprising a second cable, a connector block having longitudinal passages through which said cables extend, and stop means for the block on the first cable above the block and on the second cable below the block.

10
15
7. A container for waste material such as paper according to claim 6 in which there is a coiled spring on the second cable between the block and the stop on this cable below the block.
